US012172064B2

(12) United States Patent
Joseph

(10) Patent No.: US 12,172,064 B2
(45) Date of Patent: Dec. 24, 2024

- (54) **BASKETBALL SYSTEM FOR TRACKING AND PRESENTING OFF THE DRIBBLE SHOOTING STATISTICS**

(71) Applicant: **Shoot-A-Way, Inc.**, Upper Sandusky, OH (US)

(72) Inventor: **John G. Joseph**, Upper Sandusky, OH (US)

(73) Assignee: **Shoot-A-Way, Inc.**, Upper Sandusky, OH (US)

(*) Notice: Subject to any disclaimer, the term of this patent is extended or adjusted under 3 U.S.C. 154(b) by 93 days.

(21) Appl. No.: 18/081,118

ABSTRACT

Systems for tracking off the dribble shooting statistics are disclosed. Controller(s) receive data from a user interface indicating selection of pass receipt locations and certain of those locations where a user intends to perform a basketball move, program a launching device to pass basketballs to the selected pass locations, record and present shooting performance information for each of the passes, including separately recording and presenting such shooting performance information for those locations where the user intends to perform a basketball move.

**BASKETBALL SYSTEM FOR TRACKING
AND PRESENTING OFF THE DRIBBLE
SHOOTING STATISTICS**

**CROSS-REFERENCE TO RELATED
APPLICATIONS**

This application is a continuation-in-part of U.S. application Ser. No. 17/160,929 filed Jan. 28, 2021, which is a continuation-in-part of U.S. application Ser. No. 16/894,005 filed Jun. 5, 2020, which claims the benefit of U.S. Provisional Patent Application No. 62/858,524 filed Jun. 7, 2019, the disclosures of which are hereby incorporated by reference as if fully restated herein.

TECHNICAL FIELD

Exemplary embodiments relate generally to devices, systems, and methods for recording shooting statistics in association with one or more locations other than where the basketballs are passed, such as part of one or more passing drills.

**BACKGROUND AND SUMMARY OF THE
INVENTION**

Basketball return machines exist which assist a basketball player by returning made shots, and usually at least some missed shots, to the player such that the player does not have to spend time retrieving the basketballs. This way, the player is able to fit more shots into a given practice session. Some basketball return machines use a guide or track to direct basketballs towards a player. Other basketball return machines use launching devices to eject basketballs in various directions on a playing area. Exemplary basketball return machines include, without limitation, THE GUN machines available from Shoot-A-Way, Inc. of Upper Sandusky, Ohio (shootaway.com/) and DR. DISH machines available from Airborne Athletics, Inc. of Minneapolis, Minnesota (www.drdishbasketball.com/).

In order to provide the player with feedback regarding his or her shooting performance during a given practice session, detection devices are sometimes used to monitor the player's performance. Such detection devices may take the form of flappers which are placed along the route a basketball would take during or after passing through the rim and are physically moved or contacted when a basketball moves along such a route, thus indicating a successfully made shot. Such devices are subject to physical wear, jamming, and may disrupt the basketball's travel. Other exemplary detection devices include photo-eyes. Such photo-eyes may be mounted in close proximity to a basketball hoop and monitor for changes in the ambient light created when a basketball passes through the hoop. Such photo-eyes are subject to inaccurate readings due to changes in ambient lighting conditions which may be caused, for example, by the net shifting in front of the photo-eye, reflections, flash photographs, or lights being turned on or off. Additionally, all of the above detection devices may be difficult to appropriately position in relation to the basketball goal. What is needed is a basketball launching device with a camera for detecting made shots.

A basketball launching device with a camera for detecting made shots is provided. The basketball launching device may comprise an interface for selecting pass receipt locations on a playing area where basketballs will be ejected for a player to receive and shoot towards a basketball goal. The

interface may comprise a rendering of a basketball playing area. The interface may be configured to receive a user's selection of one or more of a number of selectable areas on the rendering where the selectable areas are positioned to correspond with actual locations on the playing area so that the player knows where to stand to receive the ejected passes.

The camera may be mounted on the basketball launching device and may be positioned to capture images of the underside of the rim. The camera may be configured to capture images as basketballs are shot by a player towards the basketball goal. The camera may feed the captured images to a controller. The controller may comprise a machine learning model configured to determine if no basketball is detected within the image, a basketball is detected but has not passed through the rim, or a basketball is detected that has passed through the rim. A made shot may be determined where captured images are received with a basketball in the frame which has passed through the rim. Otherwise, a missed shot may be recorded. The machine learning model may comprise a neural network trained from a large dataset of images. The controller may record a made shot or a missed shot as determined by the model.

A performance report may be generated comprising percentages of successfully made shots for each pass receipt location the basketballs were ejected and/or shooting location where shots were taken. The performance report may comprise a rendering which may substantially match the rendering on the interface. The percentages of successfully made shots may be provided on the rendering of the performance report at the pass receipt location and/or the shooting locations the basketballs were ejected to so that a user can quickly assess their areas of strength and weakness.

In many cases, it may be desirable for users to practice shooting off the dribble. Such off the dribble shooting may include, for example without limitation, where a player takes a shot while moving or in an otherwise non-stationary position. Such off the dribble shooting may include, alternatively or additionally, as another example and without limitation, where the player takes a shot after performing a pre-shooting basketball move and/or performing such a pre-shooting basketball move immediately before receiving a pass and immediately taking a shot. Such pre-shooting basketball moves may include any athletic, basketball related movements other than movements between the various pass receipt locations of the shooting drill. For example, without limitation, such pre-shooting basketball moves may include performing a simulated cut between pass receipt locations but exclude simply walking, jogging, running, or otherwise directly moving between the pass receipt locations. Such off the dribble shooting may include, for example without limitation, types of basketball shots to be taken such as, but not limited to, layups (e.g., reverse layup, finger roll, tear drop, power layup, double clutch, combinations thereof, or the like), bank shot, putback and tip in, jump shots, slam dunks, fade away jumpers, combinations thereof, or the like. Such off the dribble shooting may include, for example without limitation, other basketball actions taken pre- or post-receiving the pass, such as, but not limited to, movements (e.g., simulated or actual pick drill, roll, dodge, euro step, pro-hop, pro-hop euro step, power up, over-the head, combinations thereof, or the like) passing to another player or location (e.g., bounce pass, chest pass, over the head pass, touch pass, baseball pass, jump pass, blind pass, behind the back pass, combinations thereof, or the like), dribbling (e.g., cross over, between the legs dribble, behind the back dribble, wraparound, in and out dribble, v dribble,

different heights dribble, ankle breaker dribble, hesitation move, combinations thereof, or the like), triple threat positions (e.g., pivot, jab step, pump fake, drawings contact, shuffle, combinations thereof, or the like), posting up (e.g., up and under, hook shot, drop step, power move, spin and dive, sikma move, dream shake, combinations thereof, or the like), two person games (e.g., give and go, dribble pitch or handoff, pick and roll, backdoor, alley-oop, combinations thereof, or the like), various combinations of the foregoing, or the like. Such off of the dribble shooting may include, for example without limitation, various drills incorporating one or more of the same. One or more of the foregoing examples may constitute a basketball move, for example without limitation. One or more of the foregoing examples, except for the types of basketball shots examples, may constitute a pre-shooting basketball move, for example without limitation. In exemplary embodiments, without limitation, such pre-shooting basketball moves comprise dribbling after receiving a pass from the launching device but before making a shooting attempt. Alternatively, or additionally, without limitation, such pre-shooting basketball moves comprise athletic movements of the user after making a shooting attempt at a first one of the pass receipt locations, but before making a shooting attempt at a second one of the pass receipt locations, that is not direct movement between the first and second one of the pass receipt locations and/or movement solely intended for transportation of the player between the first and second one of the pass receipt locations. Such pre-shooting basketball moves may be made immediately before and/or after receiving a pass at a pass receipt location.

In exemplary embodiments without limitation, such pre-shooting basketball moves may be those which are configured to simulate game conditions and may exclude exercise-related movements. For example, without limitation, the pre-shooting basketball move may be performed to simulate game conditions such as dribbling to get open, performing a juke, pick and roll, running off a pick, combinations thereof, or the like. As a further example, without limitation, such pre-shooting basketball moves may exclude purely exercise-related movements such as line drills, jogging laps, pushups, crunches, weight lifting, combinations thereof, or the like.

Such off of the dribble shooting may be in contrast to stationary shots such as, but not limited to, free throws, planted feet shots, stationary catching and shooting attempts, combinations thereof, or the like. Such off of the dribble shooting may more realistically simulate game conditions, provide an increased workout, combinations thereof, or the like. However, particularly in an environment where shooting statistics are tracked and reported for the player or a third party to view, such as but not limited to, in a ranking across a team, group, multiple sessions, for a coach, parent, or other third party to view, a user may be reluctant to incorporate such off of the dribble shooting practice as their shooting performance statistics are likely to decrease due to the increased difficulty of such shooting attempts. Therefore, what is needed is separate tracking of off of the dribble shooting statistics.

Systems and methods are provided for tracking such off of the dribble shooting statistics, particularly in an automated fashion. Such systems and methods may track and/or provide such off of the dribble statistics in a manner which indicates the off of the dribble nature of such statistics or otherwise distinguishes such statistics from other shooting statistics. The interface associated with the basketball return machine may comprise options to select, or provide instruction for, such off of the dribble shooting. Such instructions

may, in exemplary embodiments without limitation, be provided in the form of selectable areas, travel paths, and/or action markers. Shooting statistics for such off of the dribble shooting attempts may be separately tracked, or otherwise so categorized in a performance report such as by the controller and/or report generator. Such statistics may be tracked for the user across a team, group, multiple sessions, for a coach or third party to review. In exemplary embodiments, multiple such basketball launching devices may be utilized in a space, such as in a gym, and such statistics may be transmitted to a scoreboard at the space. The scoreboard may be configured to separately display such off of the dribble shooting statistics.

Basketball drills are known which generally involve passing a basketball from a first location to one or more other locations where the basketball is caught and shot towards the basketball goal. Such passing drills may be a form of off the dribble shooting, such as catch and shooting attempts. Conventionally, basketball passing machines record shooting statistics for locations where a basketball is programmed to be passed. However, such statistics may not accurately reflect where a basketball shot is actually attempted, such as during such a passing drill and/or off the dribble shooting. What is needed is a machine with the ability to record statistics at locations other than passing locations.

Systems, methods, and devices are disclosed which facilities assignment of shooting statistics to one or more shooting locations which may be different from programmed pass receipt locations. In exemplary embodiments, without limitation, one or more locations for receiving a pass are indicated, and one or more locations are indicated for assigning the shooting statistics. Such indications may be made at a user interface, which may include a rendering of certain basketball court lines or elements, by way of non-limiting example, for reference. For example, without limitation, a passing location may be indicated and multiple shooting locations may be indicated. The order of the shooting locations may be automatically assigned and/or designated by the user. The machine may be programmed to pass basketballs to the pass location where a player catches them as passes them to players at the various designated shooting locations. Alternatively, or additionally, the player may catch a pass at the pass location and dribble or otherwise travel to the various designated shooting locations and attempt a shot before returning to the pass receipt location. Regardless, statistics from passing drills and/or off the dribble or other drills may be more accurately scored.

Shooting performance reports may be generated which visually represent the shooting statistics at the designated shooting locations rather than passing locations. Such shooting performance reports may be made at the user interface and/or may include the rendering of certain basketball court lines or elements, by way of non-limiting example, for reference.

The systems, methods, and/or devices may operate by assuming that the player actually takes a shot from the designated location(s), though such is not necessarily required. Detectors for detecting made/missed shots may be configured to detect made or missed shots and report the same to one or more controllers, which may associate them with a respective shooting location based on programmed passing and/or order information. For example, a first pass may be associated with a first shooting position, a second pass with a second shooting position, and so forth. The results from such drills may be recorded as off of the dribble shooting statistics, though such is not necessarily required.

Further features and advantages of the systems and methods disclosed herein, as well as the structure and operation of various aspects of the present disclosure, are described in detail below with reference to the accompanying figures.

BRIEF DESCRIPTION OF THE DRAWINGS

In addition to the features mentioned above, other aspects of the present invention will be readily apparent from the following descriptions of the drawings and exemplary embodiments, wherein like reference numerals across the several views refer to identical or equivalent features, and wherein:

FIG. 1 is a front view of an exemplary basketball launching device having a camera-based detection system in accordance with the present invention located near a basketball goal on a playing area;

FIG. 2 is a side view of the FIG. 1 device;

FIG. 3 is a front view of an exemplary location selection display;

FIG. 3B is a front view of an exemplary off of the dribble display;

FIG. 3C is a front view of another exemplary off of the dribble display;

FIG. 4 is a side view of the FIG. 1 device with certain elements of the basketball launching device removed to illustrate additional components, exemplary basketballs are also illustrated;

FIG. 5 is an exemplary image of a basketball passing through the hoop as seen by the camera of the FIG. 1 device;

FIG. 6 is a flow chart with exemplary logic for operating the FIG. 1 device;

FIG. 7 is a flowchart of exemplary logic for creating a machine learning model for use with the device of FIG. 1;

FIG. 8 is a front view of an exemplary performance report;

FIG. 9 is a front view of another exemplary performance report with off of the dribble shot tracking;

FIG. 10 is front view of another exemplary performance report with off of the dribble shot tracking;

FIG. 11 is front view of another exemplary performance report with off of the dribble shot tracking;

FIG. 12 is a front view of another exemplary performance report with off of the dribble shot tracking;

FIG. 13 is a front view of another exemplary performance report with off of the dribble shot tracking;

FIG. 14 is a perspective view of an exemplary facility with multiple basketball launching devices and an exemplary scoreboard;

FIG. 15 is a plan view of an exemplary multi-facility competition system in accordance with the present invention;

FIG. 16 is a detailed front view of an exemplary scoreboard for use with the system of FIG. 15;

FIG. 17 is a detailed plan view of an exemplary user interface for facilitating passing drills for use with the basketball launching device of FIG. 1 illustrating an exemplary programmed passing drill and an exemplary performance report for the drill;

FIG. 18 is a detailed plan view of the user interface of FIG. 17 illustrating another exemplary programmed passing drill with another exemplary performance report;

FIG. 19A is a detailed plan view of an exemplary user interface for facilitating passing drills for use with the device of FIG. 1 illustrating an exemplary passing drill being programmed;

FIG. 19B is a detailed plan view of the user interface of FIG. 19A undergoing further programming for the exemplary passing drill;

FIG. 19C is a detailed plan view of the user interface of FIG. 19A undergoing further programming for the exemplary passing drill;

FIG. 19D is a detailed plan view of the user interface of FIG. 19A with an exemplary performance report for the exemplary passing drill; and

10 FIG. 20 is a flow chart with exemplary logic for operating the device of FIG. 1 under the exemplary passing drills of any of FIGS. 17-19D.

DETAILED DESCRIPTION OF EXEMPLARY EMBODIMENT(S)

Various embodiments of the present invention will now be described in detail with reference to the accompanying drawings. In the following description, specific details such as detailed configuration and components are merely provided to assist the overall understanding of these embodiments of the present invention. Therefore, it should be apparent to those skilled in the art that various changes and modifications of the embodiments described herein can be made without departing from the scope and spirit of the present invention. In addition, descriptions of well-known functions and constructions are omitted for clarity and conciseness.

Embodiments of the invention are described herein with reference to illustrations of idealized embodiments (and intermediate structures) of the invention. As such, variations from the shapes of the illustrations as a result, for example, of manufacturing techniques and/or tolerances, are to be expected. Thus, embodiments of the invention should not be construed as limited to the particular shapes of regions illustrated herein but are to include deviations in shapes that result, for example, from manufacturing.

FIG. 1 is a front view of an exemplary basketball launching device 10 and FIG. 2 is a side view of the basketball launching device 10. The basketball launching device 10 may comprise a support structure 12. The support structure 12 may comprise a frame, platform, rigid members, combinations thereof, or the like. A number of wheels 14 may be mounted to the support structure 12 which permit movement of the basketball launching device 10 around a playing area 30. A housing 16 may be mounted to the support structure 12. The housing 16, in exemplary embodiments, may be mounted to the support structure 12 in a rotatable manner. One or more apertures 18 may be located in the housing 16. 50 At least a first one of the apertures 18 may be sized to permit basketballs 60 to be ejected therethrough to various pass receipt locations at the playing area 30. The first one of the apertures 18 may be located on a front of the housing 16, though any location may be utilized. A second one of the apertures 18 may be located on an upper portion of the housing 16 and may be sized to permit the basketballs to enter the housing 16 through the second one of the apertures 18. In other exemplary embodiments, the housing 16 is not required or is provided outside the travel path of the basketball.

The support structure 12 may comprise a frame 20, at least a portion of which may extend vertically. At least a portion of the frame 20 may be collapsible, though such is not required. The frame 20 may comprise one or more support members 22. At least some of said support members 22 may be adjustable in length. In exemplary embodiments, at least some of the support members 22 may comprise

telescoping poles. In exemplary embodiments, four support members 22 may extend upwardly and outwardly from the support structure 12 in a splayed fashion, though any number and configuration of support members 22 may be utilized. The support member 22 may, in exemplary embodiments, be selectively collapsible.

A net 24 may be attached to one or more of the support members 22. Openings in the net 24 may be sized to prevent the basketballs 60 from passing therethrough. The net 24 may be configured to create a funnel shape when mounted to said support members 22 such that basketballs 60 gathered in the net 24 are directed towards the housing 16 where they may be received through one or more openings, such as but not limited to, the second one of the apertures 18. However, any size, shape, and type of net 24 may be utilized. Alternatively, or in addition, one or more guide tracks may extend between the bottom of the net 24 and the housing 16.

The basketball launching device 10 may be placed in proximity to a basketball goal 40 by a user, such as directly below a rim 46 of the goal 40. The basketball goal 40 may be regulation type, height, size and configuration, though such is not required. The basketball goal 40 may comprise a post 42 which extends to the playing area 30, a backboard 44, the rim 46, and a net 48, for example without limitation. For example, without limitation, the rim 46 may be positioned 10 feet above the playing area 30.

Some or all of the frame 20 may be adjustable. For example, without limitation, the frame 20 may comprise one or more mechanisms for collapsing the support members 22, the net 24, and/or the frame 20. In this way, the basketball launching device 10 may be selectively reduced in size. In exemplary embodiments, the basketball launching device 10 may be sufficiently reduced in size so as to fit through a standard size doorway, though such is not required. As another example, without limitation, the frame 20 may comprise one or more mechanisms for expanding the support members 22, the net 24, and/or the frame 20. In this way, the basketball launching device 10 may be selectively increased in size. In exemplary embodiments, the basketball launching device 10 may be positioned and sufficiently increased in size such that one or more upper edges of the net 24 extend above the rim 46 of the basketball goal 40 when so positioned. When expanded, the net 24 may create a sufficiently sized top opening to accommodate most, or all, of a user's made shots as well as at least some, or all, of the user's missed shots, which are gathered by the net 24 and returned to the housing 16.

In still other exemplary embodiments, adjustment of the net 24 may be achieved by adjustment of the support members 22, with or without adjustment of the frame 20. FIG. 1 illustrates an exemplary configuration of the basketball launching device 10 with the net 24 positioned below the rim 46 and FIG. 2 illustrates an exemplary configuration of the basketball launching device 10 with the net 24 positioned above the rim 46 of the basketball goal 40. Any height of the net 24 in a collapsed and/or expanded position may be utilized.

At least one camera(s) 26 may be mounted to the basketball launching device 10. In exemplary embodiments, the camera(s) 26 may be mounted to the frame 20. For example, without limitation, the camera(s) 26 may be mounted to an upper portion of the frame 20. The camera(s) 26 may be positioned to face upwardly, or at an upward angle. In this way, the camera(s) 26 may be located and oriented to capture a view of the underside of the rim 46 of the basketball goal 40 when the basketball launching device 10 is placed in proximity to the basketball goal 40. However, any location

of the camera(s) 26 may be utilized, such as but not limited to, on the housing 16. The camera(s) 26 may, as another example without limitation, be mounted on one or more members which extend through the net 24. In other exemplary embodiments, the camera(s) 26 may be positioned on a portion of the frame 20 outside of the net 24. Regardless, the camera(s) 26 may be configured to capture images of rim 46 and any basketballs 60 passing therethrough. Stated another way, the camera(s) 26 may be configured to capture images of made shots.

The camera(s) 26 may be mounted to the frame 20 or other component of the basketball launching machine 10 in an adjustable fashion. The camera(s) 26 may be mounted to the frame 20 or other component of the basketball launching machine 10 in a detachable fashion. In other exemplary embodiments, the camera(s) 26 may be permanently affixed to the frame 20 or other component of the basketball launching machine 10.

In other exemplary embodiments, other types of detectors for detecting made shots may be provided at, or in association with, the basketball launching machine 10 in place of, or in combination with, the camera(s) 26 at the same or different locations as the camera(s) 26. Such detectors may comprise, for example without limitation, photo eyes, flappers, audio sensors, proximity detectors, combinations thereof, or the like. Such detectors may be provided on the basketball launching machine 10, such as on the frame 20, the housing 16, combinations thereof, or the like. Alternatively, or additionally, such detectors may be in electronic communication with the basketball launching machine 10 or components thereof, the electronic devices 70, combinations thereof, or the like such as but not limited to, by way of wired or wireless connections.

An interface 50 may be provided for receiving user input and/or displaying information. The interface 50 may comprise one or more physically depressible buttons, electronic icons capable of direct or indirect selection, one or more electronic displays, one or more touch screens, combinations thereof, or the like. The interface 50 may be connected to the frame 20. Alternatively, the interface 50 may be mounted to the housing 16 or other component of the basketball launching machine 10. Any size, shape, or location of the interface 50 may be utilized. Alternatively, or additionally, the interface 50 may be provided on one or more personal electronic devices 70 such as, but not limited to, a smartphone, a tablet, a personal computer, some combination thereof, or the like. Such personal electronic devices 70 may be physically separate from the basketball launching machine 10 or physically integrated therewith. For example, without limitation, the personal electronic devices 70 may be permanently mounted to one or more components of the basketball launching machine 10. In other exemplary embodiments, the personal electronic devices 70 may be configured for selective and/or temporary mounting to the frame 20, housing 16, or other component of the basketball launching machine 10 such as, but not limited to, by way of a holder or mounting device.

FIG. 3 is a detailed view of the interface 50 with an exemplary location selection display 51. The interface 50 may comprise a rendering, illustration, or other visual depiction 52 of elements of an exemplary playing area 30, such as but not limited to a regulation basketball court. The visual depiction 52 may comprise, for example without limitation, depictions of a baseline, a key, a three-point arc, a basketball goal, combinations thereof, or the like. Any size, shape, arrangement, type, or kind of such basketball playing area

elements or regulation or non-regulation type playing areas may be provided as part of the visual depiction 52 on the interface 50.

The location selection display 51 may comprise a number of selectable areas 62. The selectable areas 62 may be located at various positions on the visual depiction 52 to correlate with pass receipt positions on the playing area 30. The selectable areas 62 may be selected by the user to create custom shooting arrangements. The selectable areas 62, in exemplary embodiments, may be visually depicted as indicia such as but not limited to a circle though any size, shape, color, type, or the like of such selectable areas 62 may be utilized.

In exemplary embodiments, the interface 50 may comprise a touch screen. In such embodiments, the visual depiction 52 may be electronically generated electronic icons at the touch screen. The selectable areas 62, in such embodiments, may already be visible on the interface 50, such as in the form of indicia or icons, and may change when selected. In other such embodiments, the selectable area 62, such as in the form of indicia or icons, may not be visible and may become visible when the corresponding area of the interface 50 is selected. Such selection may be performed by direct, individual, physical contact, though such is not required. The touch screen may comprise a resistive, capacitive, or other type of touch screen. Some or all of the selectable areas 62 may be physically and/or electrically separated from one another or may be part of an undivided touch screen, display, panel, or the like.

In other exemplary embodiments, the interface 50 may comprise an electronic display. In such embodiments, the visual depiction 52 may be electronically generated on the electronic display. The selectable areas 62, in such embodiments, may already be visible on the interface 50, such as in the form of indicia or icons, and may change when selected. Such selection may be performed by one or more selection devices 64. Such selection devices 64 may permit interaction with the images displayed on the electronic display. For example, without limitation, such selection devices 64 may comprise a keypad, mouse, buttons, arrows, some combination thereof, or the like. The electronic display may comprise an LCD, cathode ray, OLED, plasma, or other type of electronic display.

In still other exemplary embodiments, the interface 50 may comprise a static panel. In such embodiments, the visual depiction 52 may be painted, printed, integrally formed, or otherwise provided on the interface 50 in a permanent or semi-permanent fashion. The selectable areas 62, in such embodiments, may comprise buttons. The selectable areas 62 may comprise illumination devices or the like which are configured to indicate whether the selectable areas 62 have been selected by a user. Such selection may be performed by direct, individual, physical contact, though such is not required.

Once selected, the selected ones of the selectable areas 62 may be changed, such as by illumination, highlighting, color changes, appearance, disappearance, shape change, number or other indication change, filled in, combinations thereof, or the like.

The selectable areas 62 may be provided at various locations on the visual depiction 52. The selectable areas 62 may be circular in shape, though any size and shape selectable areas 62 may be utilized. The selectable areas 62 may be located at spaced angular positions along the visual depiction 52. For example, without limitation, a number of selectable areas 62 may be positioned on or along the visual depiction of the three-point arc 56. In exemplary embodi-

ments, some of the selectable areas 62 may be located inside the three-point arc 56 and other selectable areas 62 may be located outside of the three-point arc 56, though such is not required. Alternatively, or in addition, some or all of the selectable areas 62 may be located within or around the visual depiction of the key 58. The selectable areas 62 may, alternatively or additionally, be provided in visual correlation to a visual depiction of a baseline 54. Any size, shape, number, or arrangement of selectable areas 62 may be utilized.

Each of the selectable areas 62 may comprise one or more markers 66. The markers 66 may comprise numbers, letter, symbols, some combination thereof or the like. The markers 66 may provide nomenclature for the selectable areas 62 as well as the corresponding shooting positions on the playing area. The interface 50 may be configured to monitor for, and/or receive, a user selection of one or more of the selectable areas 62 to create a custom basketball practice arrangement. The selectable areas 62 may be individually selected by physical touch in a direct or indirect manner. The selectable areas 62 may form input locations for receiving user input.

Alternative or in addition to the embodiments described herein, a number of predetermined sets of selectable areas 62 may be preprogrammed to define pre-made practice arrangements. Such pre-made practice arrangements may be made available by way of certain ones of said selectable areas 62. In such embodiments, the interface 50 may be configured to permit the user to select one or more such predetermined programs as an alternative to, or in addition to, creating a custom practice arrangement.

The selectable areas 62 may be arranged on the visual depiction 52 to visually correspond with pass receipt locations at the playing area. In this way, the player knows where to stand to receive passes from the basketball launching machine 10 and the player is able to select particular areas to focus on, such as areas of weakness. The selectable area 62 may be provided on a 1:1 basis with such pass receipt locations, though any ratio may be utilized.

The interface 50 may comprise one or more areas 67 for selecting additional options such as, but not limited to, a time delay between passes, a number of basketballs per location, and the like. In exemplary embodiments, the separate area(s) 67 may not be required and such options may be selected at the area with the visual depiction 52. The areas 67 may be part of the interface 50, or be separate therefrom. The areas 67, for example without limitation, may comprise further selectable areas of a touch screen, icons on an electronic display, dedicated button(s), combinations thereof, or the like.

FIG. 3B and FIG. 3C are detailed views of the interface 50 with exemplary off of the dribble displays 71. In exemplary embodiments, the interface 50 may be configured to display travel paths 92 for a player 72. The travel paths 92, for example without limitation, may be displayed as straight lines, squiggle lines, color coded lines, dashed lines, other symbols, line type, colors, combinations thereof, or the like. The travel paths 92 may be configured to convey instructions to the player 72 on locations to run or otherwise travel to before or after receiving a basketball pass from the basketball launching machine 10 at a given one of the pass receipt locations forming part of the custom basketball practice arrangement. The travel paths 92 may comprise out-and-back paths, such as the travel path 92 shown from pass receipt location labeled "1" in the illustrated embodiment. The travel paths 92 may comprise shooting paths, such as the travel path 92 shown from a pass receipt location

marked "20" in the illustrated embodiment to a shooting location closer to the visual depiction 52 of the basketball goal, which may indicate that the player 72 should perform a layup shot. The travel paths 92 may comprise routes between pass receipt locations, such as the travel path 92 between pass receipt locations labeled "5" and "7" in the illustrated embodiment. Of course, the illustrated embodiment is merely exemplary and is not intended to be limiting. Any number or type of travel paths 92 between any number of locations may be utilized. Likewise, any way of representing the travel paths 92 may be utilized. The travel paths 92 may be provided with some or all of the selectable locations 62 selected by the user and forming part of the custom basketball practice arrangement. The type of travel paths 92 displayed may be pre-selected or may be determined by the user.

Additionally, or alternatively, action markers 91 may be provided at the off of the dribble display 71 to indicate certain types of shots to be performed before and/or after receiving a basketball pass from the basketball launching device 10. Such action markers 91 may be provided at, or in association with, some or all of the selectable locations 62 selected by the user and forming part of the custom basketball practice arrangement. The type of actions indicated by the action markers 91 may be predetermined or may be selected by the user. The action markers 91 may convey pre- or post-pass receipt actions to be performed by the user and to be recorded accordingly. Such post pass receipt actions may include, for example without limitation, taking a certain type of shot, dribbling the basketball, passing the basketball to a second player who takes one or more particular actions pre- and/or post-receiving the pass from the first player, combinations thereof, or the like. For example, without limitation, such post pass receipt actions may include a drill where a first player receives a pass at the top of the key and passes to a second player coming off a real or simulated pick closer to the basket. Such passes may be indicated by dashed lines as shown with regard to FIG. 3C, though any such indication may be utilized.

In the example shown in FIG. 3C, the first player may stand at or near a location on the basketball playing area 30 corresponding to selectable area 62 labeled "5" to receive a pass from the basketball launching device 10. A second player may stand at or near a location on the basketball playing area 30 corresponding to selectable area 62 labeled "12", travel as indicated by travel path 92 off a simulated pick as indicated by the action marker 91A labeled "P", to receive a pass from the first player as indicated by the action marker 91B in dashed line from where the second player performs a jump shot as indicated by the action marker 91C labeled "J". This example is provided without limitation. Any known or yet to be developed drills or other actions may be incorporated into such off of the dribble displays 71. Selection of such drills may be made by selection of pre-programmed options at said off of the dribble selection area 69 or other portion of said interface 50, and/or creation of custom such drill at said off of the dribble selection area 69 or other portion of said interface 50. The labels for such action markers 91 and other items shown and/or described herein are merely exemplary and are not intended to be limiting. Any description, abbreviation, image, animation, icon, symbol, alphanumeric character(s), line type, colorization, combinations thereof, or the like may be used as action markers 91 to represent any type of kind of action. Different or the same such action markers 91 may be used to represent the same or different kinds of actions. Such action markers 91 may be changed periodically, such as

according to user preference. A legend display may be selectively displayed to a user to demonstrate the meaning of each such action marker 91. In exemplary embodiments, some or all of such instructions may be provided by way of live or pre-recorded audio and/or video played at or through the interface 50 or related device(s).

An off the dribble selection area 69 may be provided at the off of the dribble display 71. The off the dribble selection area 69 may permit a user to select certain pre- or post-passing options which affect the travel paths 92 and/or action markers 91 displayed such as type, length, and number of travel paths, pre-programmed options, shot types, post pass receipt actions, pass receipt locations for such selectable areas 62, travel paths 92, and/or action markers 91, combinations thereof, or the like. Such options may be presented in a menu format. Alternatively, or additionally, such options may be selected by a click and drag, tracing, scrolling, swiping, or other movement at the interface 50, particularly where said interface 50 comprises a touch screen, and/or at said selection devices 64. The off of the dribble selection area 69 may be physically and/or electronically separated from the off of the dribble display 71 or form a part thereof.

The off the dribble selection area 69 may be provided as a prompt upon selection of a selectable area 62, selection of an icon or other marker representing the same, or as a separate option or menu area of the interface 50. The off the dribble selection area 69 may comprise an option for the user to designate shots associated with a given one of the selectable areas 62, and the associated pass receipt location, as being associated with an off the dribble shooting attempt. Such selection may be relayed to the controller 68 which may be configured to cause all made/missed data received from the detectors, such as but not limited to the camera(s) 26, to be recorded with an indication that such data is associated with off the dribble shooting attempts. This may permit the separate tracking and display of statistics related to such off the dribble shooting attempts.

The travel paths 92 and/or action markers 91 may be used to convey instructions to the player to perform at the playing area 30 as part of the custom basketball practice routine. These may be used to simulate game conditions, provide an enhanced workout, perform certain drills, combinations thereof, or the like.

Examples of such items which may be indicated by the travel paths 92 and/or action markers 91 and/or selected at the off the dribble section area 69 and/or interface 50 include, but are not limited to, types of basketball shots to be taken such as, but not limited to, layups (e.g., reverse layup, finger roll, tear drop, power layup, double clutch, combinations thereof, or the like), bank shot, putback and tip in, jump shots, slam dunks, fade away jumpers, other basketball actions taken pre- or post-receiving the pass, such as, but not limited to, movements (e.g., simulated or actual pick drill, roll, dodge, euro step, pro-hop, pro-hop euro step, power up, over-the head, combinations thereof, or the like) passing to another player or location (e.g., bounce pass, chest pass, over the head pass, touch pass, baseball pass, jump pass, blind pass, behind the back pass, combinations thereof, or the like), dribbling (e.g., cross over, between the legs dribble, behind the back dribble, wraparound, in and out dribble, v dribble, different heights dribble, ankle breaker dribble, hesitation move, combinations thereof, or the like), triple threat positions (e.g., pivot, jab step, pump fake, drawings contact, shuffle, combinations thereof, or the like), posting up (e.g., up and under, hook shot, drop step, power move, spin and dive, sikma move, dream shake, combinations thereof, or the like), two person games (e.g., give and

go, dribble pitch or handoff, pick and roll, backdoor, alley-oop, combinations thereof, or the like), various combinations of the foregoing, or the like. This list is merely exemplary and is not intended to be limiting. Any type or kind of such actions, already known or yet to be developed, may be selected, displayed, and or tracked in the same or separate categories.

In exemplary embodiments, these various pre- and/or post-pass receipt actions as indicated by the travel paths 92 and/or the action markers 91 may be tracked in a single off of the dribble category separate from, or selectively separable from, other shooting statistics. Alternatively, or additionally, each of the various pre- and/or post-pass receipt actions as indicated by the travel paths 92 and/or the action markers 91 may be tracked in their own subcategory of off of the dribble category separate from, or selectively separable from, other shooting statistics.

In exemplary embodiments, without limitation, the machine 10 may be configured to increase a time between launching basketballs for each of said pass receipt locations selected by the user at the interface 50 where the user also indicated an association with off the dribble shooting attempts. This may provide the user with additional time to complete one or more basketball moves immediately before or after receiving the basketball pass at the respective one of the pass receipt locations. The time increase may be added to a default timing and/or a programmed timing indicated by the user at the interface 50. The time increase may be a predetermined amount, such as but not limited to a number of seconds, or may be manually programmed by the user at the interface 50. The timing increase may apply only to those pass receipt locations that the user has indicated, such as by way of the interface 50, an association with off the dribble shooting attempts. In other exemplary embodiments, such as where selection of a pre-programmed subset of pass receipt locations and/or drill is selected, the timing increase may be automatically applied to any pass receipt locations in the pre-programmed subset or drill associated with such off the dribble shooting attempts. Alternatively, or additionally, the speed at which basketballs are launched may be decreased for such pass receipt locations associated with off the dribble shooting attempts to accomplish an increased delay between such passes.

In exemplary embodiments, without limitation, one or more pre-made practice arrangement options may be provided at said interface 50. Each of these pre-made practice arrangement options may comprise a subset of the pass receipt locations and/or one or more off the dribble selections already associated with certain of said pass receipt locations in said subset.

FIG. 4 is a side view of the basketball launching device 10 with certain elements of the housing 16 removed to illustrate the launcher 28. The launcher 28 may be configured to launch one or more basketballs 60 to one or more pass receipt locations at the playing area 30 for a player 72 to catch and shoot towards the basketball goal 40. For example, without limitation, the launching device 28 may comprise a catapult arm, thrower, wheeled device, some combination thereof, or the like. Any kind or type of launching device 28 may be utilized. The launcher 28 may be mounted to the housing 16 and/or the support structure 12 in a rotatable manner, though such is not required.

The interface 50 may be placed in electronic communication with a controller 68. The controller 68 may be located at the housing 16, though any location of the controller 68 may be utilized, including but not limited to at a remote location such as a server and/or personal electronic device

70. The controller 68 may comprise one or more electronic storage devices with executable software instructions and one or more processors. Alternatively, or in addition, the controller 68 may be part of one or more other components 5 of the basketball launching device 10 including but not limited to, the camera(s) 26 and the interface 50. The controller 68 may be configured to receive electronic signals from the interface 50 regarding the user's selection of the selectable areas 62 to form a custom practice arrangement 10 and may program the launcher 28 to pass basketballs 60 to each of the pass receipt locations at the playing area 30 corresponding to each of selectable areas 62 selected by the user at the interface 50 to perform the custom practice arrangement. The controller 68 may be configured to, alternatively or additionally, receive input from the interface 50 15 including user selection of the selection devices 64, area 67, off of the dribble selection area 69, pre-programmed drill, user preferences, other options, some combination thereof, or the like and program the launcher 28 and/or display such 20 user selections at the interface 50 in accordance with the received input.

The basketball launching device 10 may be positioned in proximity to the basketball goal 40 such that the basketballs 60 passing through the rim 46, and at least some of the basketballs 60 bouncing off the backboard 44 but not necessarily passing through the rim 46 or otherwise resulting in a missed shot (i.e., not passing through the rim 46), may be captured in the net 24. The camera(s) 26 may be positioned to face upwardly at the bottom of the rim 46. In this way, the 25 camera(s) 26 may be configured to capture an image of the basketball rim 46 with no basketball (no ball in frame), an image of the basketball rim 46 and the basketball 60 failing to pass completely through the rim 46 (an attempted shot), or an image of the basketball 60 as it passes through the rim 30 35 46 (made shot).

FIG. 5 is an exemplary image of a basketball 60 passing through the rim 46 as seen by the camera(s) 26—i.e., a made shot. FIG. 6 is exemplary logic for use with the controller 68. The camera(s) 26 may be placed in electronic communication 40 with the controller 68. The controller 68 may be configured to receive one or more images from the camera(s) 26. Such images may comprise a video and/or one or more still images. The images may be captured continuously, periodically, at a specific time interval, sporadically, 45 some combination thereof, or the like. In exemplary embodiments, the camera(s) 26 may be configured to capture approximately 36-40 frames per second. The camera(s) 26 may be configured to capture images following the ejection of a basketball 60 by the launcher 28. For example, without 50 limitation, the camera(s) 26 may be activated immediately, or a period of time after, the launcher 28 ejects a basketball.

The controller 68 may comprise software instructions, which when executed, cause the controller 68 to receive the images from the camera(s) 26 and utilize machine learning 55 software to determine whether or not the received image comprises a basketball 60, a basketball 60 not passing through the rim 46, or a basketball 60 passing through the rim 46.

The controller 68 may comprise a number of images of a 60 rim 46 without a basketball 60, a number of images of a rim 46 and a basketball 60 not passing through the rim 46, and a number of images of a basketball 60 passing through the rim 46. In other exemplary embodiments, such images may be provided at one or more remote databases. The controller 65 68 may be configured to derive, or may be programmed with, software instructions, which may comprise one or more algorithms, configured to distinguish between images

with a basketball **60**, images without a basketball **60**, images with a basketball **60** intersecting a rim **46**, images with the basketball **60** intersecting a front portion of the rim **46**, images with a basketball **60** located within the rim **46**, images with a basketball **60** not intersecting the rim **46**, images of the basketball **60** progressing through the rim **46**, some combination thereof, or the like.

In exemplary embodiments, an attempted shot may be determined where images are received with no basketball **60** for a period of time following the ejection of a basketball **60** or images are received with a basketball **60** not passing completely through the rim **46**. In exemplary embodiments, a made shot may be determined where images are received with a basketball **60** which passes completely through the rim **46**. For example, without limitation, a basketball **60** may be determined to have completely passed through the rim **46** where the image of the basketball **60** is located within the rim **46** and/or is intersecting the front surface of the rim **46**, as generally indicated at item **74**. Alternatively, or in addition, the made shot may be confirmed by receipt of subsequent and/or further images showing a progression of the basketball **60** through the rim **46** in the manner and sequence consistent with a made shot. For example, without limitation, the machine learning software may be configured to search for images of a basketball **60** intersecting the rim **46**, as generally indicated at item **74**, in a fashion such that the basketball **60** progressively intersects more of the rim **46** for one or more frames before subsequently intersecting less of the rim **46** as is consistent with stored images of basketballs **60** passing through the rim **46**.

It may be determined with a high degree of confidence that a given basketball **60** passed through the rim **46**, and thus a basketball goal was successfully made, where the received image matches, or is within a predetermined margin of error of, the stored images of basketballs **60** passing completely through the rim **46**. Similarly, it may be determined with a high degree of confidence that a given basketball **60** did not pass through the rim **46**, and thus a basketball goal was not made, where the received image matches, or is within a predetermined margin of error of, the stored images of basketballs **60** not in the frame and/or not passing completely through the rim **46**. Such determinations made be made continuously or periodically as basketballs **60** are launched and shots are taken, or may be performed after a given practice session is completed.

FIG. 7 is a flowchart of exemplary logic for creating a machine learning model. In exemplary embodiments, a dataset comprising a number of images of a rim **46** without a basketball **60**, a number of images of a rim **46** and basketballs **60** not passing completely through the rim **46**, and a number of images of basketballs **60** passing completely through the rim **46** may be generated by taking a large number of such images. In exemplary embodiments, over 15,000 such images may be taken to form the dataset, though any number of images and any size dataset may be utilized. The images may be converted into a lossless format and may be resized as needed. A first subset of the images in the dataset may be separated for use as a training set. A second subset of the images in the dataset may be separated for use as a validation set. In exemplary embodiments, the first subset may comprise approximately 80% of the images and the second subset may comprise approximately 20% of the images. The first subset of images may be passed through a neural network to train the network to recognize each category of images. The second subset of images may be manually reviewed to properly categorize each image. The results of the first subset of images may be compared to the

second subset, where the proper categorization is known, and the process may be repeated any number of times until the neural network is configured to categorize images with an acceptable degree of error to form a model. Once results within an acceptable threshold of accuracy is achieved, the neural network may be saved as a model. The model may then be utilized during actual practice sessions. The training may be performed off site and the model may be transferred to the controller **68**. In other exemplary embodiments, the training may be performed at the controller **68**.

FIG. 8 illustrates the interface **50** with an exemplary performance report **80** for a given practice session. The report **80** may comprise the same or similar visual depiction **52** of the playing area **30**, though such is not required. The visual depiction **52** may be the same or different from the visual depiction **52** provided at other displays, such as but not limited to at the interface **50**.

The performance report **80** may comprise shooting feedback **86** located at, and corresponding to, substantially each of the selectable areas **62** forming the practice arrangement. The feedback **86** may be visually depicted with indicia of the same size and shape as the selectable areas **62**, though such is not required. For example, without limitation, the feedback **86** may be provided without such indicia, or with different types, color, size, shape, or the like characteristics compared to the selectable areas **62**. The feedback **86** may comprise a number of made shots, a number of missed shots, a percentage of made shots, a percentage of missed shots, a grade, a pass/fail indication, combinations thereof, or the like. The feedback **86** may be provided in the same or similar form, such as but not limited to, shape, font, color, size, some combination thereof, or the like, as the selectable areas **62**. For example, without limitation, the selectable areas **62** and the feedback **86** may comprise circles. In this way, the user may be able to quickly ascertain their strong and weak shooting positions. An overall number and/or percentage of made and/or missed shots, or other information, may be displayed at a second area **94**, though such is not required. In exemplary embodiments, such all number and/or percentage of made and/or missed shots, or other information, may, alternatively or additionally, be displayed at a separate display on the basketball launching device **10** or elsewhere.

The performance report **80** may be displayed at the interface **50**. The performance report **80** may be generated at the controller **68**, the interface **50**, the personal electronic device **70**, some combination thereof, or the like.

In other exemplary embodiments, the interface **50**, and/or various displays thereof, may be provided on the personal electronic device **70** in addition to, or alternatively to, at the basketball launching machine **10**. It is notable that the user of the interface **50** may be provided to the basketball player **72** or may be some other individual such as, but not limited to, a friend, parent, coach, assistant, or the like.

FIG. 9 illustrates another exemplary embodiment of the performance report **80**. The performance report **80** may be configured to track and separately display, or otherwise indicate, off of the dribble shooting. Such information may be reflective of user selections made at the off of the dribble display **71** in exemplary embodiments. For example, without limitation, data may be received from the interface **50**, such as but not limited to, from user selections made or provided at the off of the dribble display **71**, indicating user selection or one or more travel paths **92**, action markers **91**, combinations thereof, or the like. Shots made or missed, as detected by the camera(s) **26**, detectors, combinations thereof, or the like, may be separately recorded and displayed for shooting attempts associated with such off of the

dribble shooting attempts and/or specific types of shots selected. Such association may be made by way of comparing a timing of launches from the launcher 28 and the timing of detected made and/or missed basketball shots. In exemplary embodiments, without limitation, a missed shot may be determined where a certain amount of time passes since said launch from the launcher 28 with no such detection of a made shot.

In exemplary embodiments, a qualifier 86B may be provided with at least certain ones of the feedback 86 to indicate association of the particular feedback 86 with off of the dribble shooting attempts. Such qualifiers 86B may comprise “OD” for “off of the dribble”, or other indication, symbol, or the like of the travel path 92, the action markers 91, or other information about the off of the dribble nature of the shooting attempts provided to, or selected by, the user at the interface 50 for associated pass receipt and/or shooting locations. Alternatively, or additionally, different qualifiers 86B may be provided in association with an abbreviated or narrative description indicating the type of action item 91, travel path 92, and/or other type and/or kind of off of the dribble related action associated with the shooting statistics, each of which may be separately tracked, categorized, and displayed in exemplary embodiments based on user selections made at the interface 50 and data received from the detectors.

FIG. 10 illustrates another exemplary embodiment of the performance report 80. The performance report 80 may comprise a listing of feedback 86, at least some of which may comprise the qualifiers 86B. Such feedback 86 may be provided for individual pass receipt and/or shooting locations selected or provided at the interface 50 and/or overall categorizations of such statistics for one or more shooting sessions, across a team or other group, combinations thereof, or the like. Such feedback 86 may be provided together or separately, such as in listings, a scrolling manner, combinations thereof, or the like.

FIG. 11 illustrates another exemplary embodiment of the performance report 80 in the form of a ranking display 81. Players may be ranked as a team, group, members of a gym, club, or the like, or according to user preferences. Qualifiers 86B may be provided adjacent to, or otherwise in association with, certain of the feedback 86. Such feedback 86 may be provided for individual pass receipt and/or shooting locations selected or provided at the interface 50 and/or overall categorizations of such statistics for one or more shooting sessions, combinations thereof, or the like. Such feedback 86 may be provided together or separately, such as in listings, a scrolling manner, combinations thereof, or the like.

FIG. 12 and FIG. 13 illustrate other exemplary embodiments of the performance report 80. The feedback 86 may comprise percentages of made shots for each of the selectable locations 62. The feedback 86 may be color coded to indicate feedback above or below a predetermined threshold. For example, in the example provided in FIGS. 12 and 13, feedback above 70% is indicated with a red area while feedback at or below 70% is indicated in blue. Some of all of the feedback 86 may not be color coded.

A feedback category selectable area 41 may be provided as part of, or separate from, the performance report 80. A number of categories 43 for feedback 86 to be displayed at the feedback category selectable area 41. The various categories 43 may be selected by a user, such as shown by selection indicator 45, and the corresponding category 43 of feedback 86 may be generated for display at the perfor-

mance report 80. The selection indicator 45 may be, for example without limitation, a box around a selected category 43.

Such categories 43 may include, for example without limitation, career 43A (e.g., lifetime cumulative statistics for a given user), monthly 43B, catch and shoot 43C (e.g., not off the dribble), off of the dribble 43D, on the move 43E (e.g., where travel paths 92 are associated with shooting), combinations thereof, or the like. Some or all of the titles for such categories 43, such as but not limited to off of the dribble 43D and/or on the move 43E, may serve as qualifiers 86B in exemplary embodiments. In exemplary embodiments, the various categories 43 may be accessed by swiping, such as where the performance report 80 is provided on a touch screen, though other techniques may be utilized. In exemplary embodiments, the various categories 43 may be selected by touching, such as where the performance report 80 is provided on a touch screen, though other techniques may be utilized. In exemplary embodiments, off of the dribble shooting may be shooting attempts made following dribbling drills (e.g., catch the basketball, dribble it an amount, distance, time, combinations thereof, or the like, and then make a shooting attempt). On the move shooting may be shooting attempts made while the player is moving immediately before catching the basketball, and do not necessarily involve dribbling (e.g., running off a simulated or actual screen, pick and roll drill, cutting drill, combinations thereof, or the like). The on the move shooting may include off the dribble shooting, or vice-versa, though such is not required. In exemplary embodiments, on the move shooting attempts may be those associated with travel lines 92 and off the dribble shooting attempts may be those associated with action markers 91, though the reverse or other combinations may be utilized.

Cumulative feedback 86 for a given category 43 may be provided in association with each category 43. In exemplary embodiments, each category 43 may comprise at least a title, a cumulative number of made shots for the category, a cumulative number of shots taken for the category 43, and a percentage of made shots for the category 43. However, any number, type, kind, organization, and the like of such feedback 86 and such categories 43 may be utilized.

FIG. 14 through FIG. 16 illustrate exemplary competition facilitating systems. A facility 95 configured to hold one or more basketball launching machines 10 may be provided. The facility 95 may be a gym, recreation center, school facility, retail location, or any other type of kind space and/or building. The facility 95 may have a ceiling height sufficient to accommodate players shooting basketballs towards the one or more basketball launching machines 10. The facility 95 may have one or more playing surfaces, such as a wooden basketball playing floor with or without regulation or non-regulation playing line markings, configured to facilitate basketball play. One or more basketball launching machines 10 may be provided about the same or different playing areas 30. Each of the basketball launching machines 10 may be associated with a basketball goal 40, though such is not required. Netting, walls, or other dividers may be provided between each of the basketball launching machines 10.

Multiple players may practice at the one or more basketball launching machines 10 at the same or different times. Data may be transmitted from one or more of the basketball launching machines 10, associated personal electronic devices 70, combinations thereof, or the like, wired or wirelessly, to one or more scoreboards 97. The scoreboard(s) 97 may be configured to generate and/or display the performance report 80 in any embodiment, combinations thereof,

or the like shown and/or described herein. The scoreboard(s) 97 may be positioned within the facility 95, such as but not limited to, mounted to one or more walls or from a ceiling thereof, in view of some or all of the basketball launching machines 10. In exemplary embodiments, the scoreboard(s) 97 are configured to display a ranking 81 of shooting statistics or other feedback 86 for various players in a group, team, or the like. In exemplary embodiments, at least some of the statistics 86 may comprise, or consist of, statistics associated with off of the dribble shooting attempts and qualifiers 86B may be provided indicating the same. The qualifiers 86B may be configured to indicate off of the dribble shooting attempts and/or non-off the dribble shooting attempts.

The controller 68 may be configured to associate certain data received from the detector, such as the camera(s) 26, with off dribble shooting attempts based on user selections made at the off the dribble selection area 69. For example, without limitation, made/missed data from the detector may be indicated as being associated with off the dribble shooting attempts where said data is associated with pass receipt locations associated with selectable areas 62 or icons forming part of a current practice arrangement and associated with user selections made at the off dribble selection area 69.

A single interface 50 and/or controller 68 may be used to control each of the basketball launching machines 10. Alternatively, or additionally, a separate interface 50 and/or controller 68 may be provided for each of the basketball launching machines 10. In this way, a common practice routine may be provided to each of the basketball launching machines 10 for a competitive challenge by the single interface 50, or commonly programmed at each machine 10. Alternatively, separate practice routines may be provided for each of the basketball launching machines 10, such as by the single interface 50 or separate interfaces 50.

In exemplary embodiments, the scoreboards 97 may be configured to display feedback 86, such as shooting statistics, from all such basketball launching machines 10 in a given facility 95. The scoreboard 97 may periodically or continuously display feedback 86 for all users of the basketball launching machines 10 within the facility 95, or a subset of such users, such as but not limited to, current users of such machines 10. This may facilitate competition between users of machines 10 of a given facility 95. In other exemplary embodiments, the scoreboards 97 may be configured to display feedback 86 from basketball launching machines 10 in multiple facilities 95. In such embodiments, the statistics displayed may be for all users of all such machines 10 in all such facilities 95, or a subset of such users. This may facilitate competition intra-facility 95 competitions, such as but not limited to, intra-region, intra-conference, intra-state, national, or worldwide competitions. As another example, without limitation, the scoreboard 97 may be configured to display cumulative feedback 86 for all users of all machines 10 at a given facility 95 against all user of all machines 10 at another facility 95, or subsets of such users. This may facilitate intra-facility 95 competitions. In still other embodiments, the scoreboards 97 may be configured to display feedback 86 for select groups of users and/or select machines 10 of select facilities 95. This may facilitate group competitions, such as but not limited to, friends, families, teams, or the like.

The feedback 86 from multiple machines 10 and/or facilities 95 may be gathered at one or more centralized databases 89, though such is not required. Such databases 89 may, alternatively or additionally, be in electronic communication with remote devices 70 such as laptops, smartphones, tab-

lets, servers, combinations thereof, or the like. The centralized databases 89, where utilized, may be in electronic communication with each other and/or the scoreboards 97 of any number of facilities 95. User's may be able to specify relationships with facilities 95, groups (e.g., friends, families, teams, combinations thereof, or the like), regions, conferences, states, nations, combinations thereof, or the like to facilitate such scoring, display, and competition. Such information may be recorded by way of the user interfaces 50, at the databases 89, at remote devices 70, combinations thereof, or the like. A single, central database 89 may be provided for all facilities 95, for example. As another example, a database 89 may be provided for each facility 95 and each of said databases may be in communication with one another 89.

A separate scoreboard 97 may be provided in each facility 95, though such is not required. The individual machines 10, the databases 89, and/or the remote devices 70 may be in electronic communication with one or more of the scoreboards 97 and be configured to command said scoreboards 97 to display the feedback 86, including but not limited to, rankings 81 and qualifiers 86B in association with some or all of the displayed feedback 86. The feedback 86 may be displayed in any form or format, including but not limited to, as a ranking 81 and/or the same or similar to some or all of the performance report 80.

The interface 50 and various displays thereof as shown and provided herein, including but not limited to the location selection display 51, the off of the dribble display 71, and/or the performance report 80 (in any exemplary embodiment shown and/or described herein, combinations thereof, or the like) may be provided at the basketball launching machine 10, the remote personal electronic device 70, the scoreboard 97, combinations thereof, or the like.

The various selection or selectable areas shown and/or described herein, such as but not limited to selection devices 64, areas 67, off of the dribble selection area 69, and/or second area 94, may be separate from, or integrated with, the various displays such as, but not limited to, the visual depiction 52, the off of the dribble display 71, the location selection display 51, the reports 80, the shooting feedback 86, selectable areas 86, markers 66, combinations thereof, and the like such that such items are provided on a common interface 50, display, touch screen, panel, or the like or on separate displays, touch screens, panels, interfaces 50, or the like.

FIG. 17 through FIG. 19D illustrate another exemplary user interface 150. Similar items may be numbered similarly but increased by 100 (e.g., 50 to 150), though such is not necessarily the case. The user interface 150 may be provided at the passing machine 10, and/or may be remote therefrom, such as provided at one or more personal electronic devices (e.g., smartphone, tablet, computer, server, combinations thereof, or the like). The user interface 150 may comprise a touch sensitive display, such as but not limited to a touch screen. Alternatively, or additionally, the user interface 150 may comprise one or more panels with printed graphics and/or physically manipulatable objects (e.g., buttons, levers, knobs, switches, mouse, keyboard, keypad, joystick, combinations thereof, or the like). The user interface 150 may be configured to facilitate programming and operation of the machine 10 as part of a passing drill, such as in the fashion show in FIG. 20.

The user interface 150 may be generated and/or controlled by way of one or more controllers 68, which may be local to the passing machine 10 or remote therefrom (e.g., at remote servers and/or personal electronic devices). For

example, without limitation, software for operating the user interface **150** and/or passing machine **10** may be provided at the passing machine **10** and/or one or more remote locations (e.g., internet/cloud hosted). The controller(s) **68** may be configured to cause the user interface **150** to selectively provide and adjust the displays **171**, features, data, information, and/or options shown and/or described herein, and/or accept user input at the user interface **150** and adjust device **10** operations accordingly. User input may be provided by way of one or more touch inputs, gestures, manipulation of physically manipulatable objects, combinations thereof, or the like. The displays **171** may be directly manipulated, such as by way of a touch sensitive display, or may be indirectly manipulated, such as by way of adjacent buttons, switches, mouse, keyboard, keypad, joystick, combinations thereof, or the like.

The user interface **150** may include one or more displays **171**. The displays **171** may comprise one or more visual depictions **152**, such as of part of all of a regulation basketball court and/or related elements. Such visual depictions **152** may comprise, for example without limitation, renderings of one or more basketball court lines (e.g., base line, lane line, key, half court line, jump ball circle, free throw lines, three-point arc, side lines, foul lines, restricted zone boundary line, combinations thereof, or the like), one or more overlays defining one or more zones about some or all of the basketball court lines (e.g., about the three-point arc), one or more basketball passing machines, one or more basketball goals, combinations thereof, or the like. The visual depiction **152** may be consistent with various basketball rules and regulations, though such is not necessarily required.

In exemplary embodiments, without limitation, the zones of the depiction **152** may define areas for statistical scoring. In this fashion, any and all basketballs programmed for passing to one or more locations within a given zone may be grouped together for scoring purposes. In this fashion, one statistical score may be provided for each zone. In other exemplary embodiments, without limitation, the zones may be provided only for reference purposes. Alternatively, or additionally, scores from multiple locations and/or zones may be aggregated, such as but not limited to, in order to present an overall drill performance score.

The displays **171** may comprise one or more icons **162**. The icons **162** may comprise renderings of basketballs, though such is not required. Any type or kind of icon **162** may be utilized. In exemplary embodiments, without limitation, the icons **162** may be visually depicted at location(s) selected by a user. The icons **162** may be prepopulated at the displays **171** or populated upon user selection. For example, without limitation, icons **162** may be absent from the displays **171** until a location is selected by a user at the user interface **150**, and an icon **162** may be subsequently generated at the selected location. In exemplary embodiments, without limitation, locations may be selected by way of direct physical touch at a touch interface, though indirect or alternative techniques for location selection may be utilized. Icons **162** may be relocated, particularly before a program is initiated by selecting a start/stop option **142**. Relocation may be performed by touch and drag, by way of non-limiting example. As another example, without limitation, icons **162** may be initially populated at predetermined locations, such as upon selection of a preprogrammed drill option or upon initiating programming of a custom drill. Optionally, such icons **162** may be subsequently moved.

Some or all of the icons **162** may comprise one or more action markers **191**. The action markers **191** may be auto-

matically provided based on a type of drill selected at the user interface **150** for programming and/or the stage of the user's progression through such programming. By way of non-limiting example, where a passing drill is selected for programming, such as but not limited to at a mode option **141**, the first icon **162** generated may represent and provide a pass receipt location indication **191** (e.g., for catching and passing or moving to another location). Each subsequent icon **162** generated may represent a shooting location and provide an order indicator (e.g., 1, 2, 3, etc.) and/or a point indicator (e.g., 2-point, 3-point, field goal, free throw, etc.). Such action markers **191** may be graphically displayed text (e.g., letters, words, number), icons, combinations thereof, or the like.

The nature of the icons **162** (e.g., as pass receipt location, catch and pass location, catch and move location, etc., or shooting location) may be manually adjusted at the user interface **150**, in exemplary embodiments without limitation.

The order number may be automatically adjusted based on the order in which the user selection is made. For example, a first relevant one of the icons **162** may be ordered as the first shooting location, the second relevant one of the icons **162** may be ordered as the second shooting location, and so forth. Alternatively, or additionally, the order may be automatically adjusted in numerical order from one side of the display **171** to another (e.g., right to left, left to right, further to closer to goal, closer to further to goal, etc.). In exemplary embodiments, without limitation, order may be automatically set to the order selected by the user where a non-serial option **145** is selected, and the order may be automatically set based on the location of the icon **162** (e.g., in sequential order from left to right, closer to further to the goal, right to left, further to closer to the goal, combinations thereof, or the like) where a serial option **145** is selected.

The point value associated with each of the icons **162** may be automatically adjusted based on the location of the icon **162** relative to certain visualization **152** elements (e.g., 2 points for icons **162** in front of the 3-point arc, 3 points for icons **162** behind the 3-point arc, 1 point for icons **162** at the foul line, etc.), such as in accordance with various basketball rules and regulations, though such is not necessarily required.

The order, point value, and/or nature of (e.g., as a pass or shooting location) the icons **162** may be manually adjusted at the user interface **150** in exemplary embodiments, without limitation. One or more of the number, location, order, point value, and/or nature of the icons **162** may be manually selected by the user to create custom basketball drills.

Alternatively, or additionally, some or all of the number, location, order, point value, and/or nature of the icons **162** may be automatically generated, such as but not limited to, upon user selection of a pre-programmed drill option, such as may be available from a library of drills. Such a library of drills may be stored locally at the device **10** and/or remote therefrom, such as at one or more remote databases. Alternatively, or additionally, some or all of the number, location, order, point value, and/or nature of the icons **162** may be programmed and/or adjusted at a remote user interface **150** (e.g., at a personal electronic device) and generated for display at the machine **10**. In this fashion, a parent, teammate, user, coach, combinations thereof, or the like, may provide remote programming and/or adjustment of a machine **10**. The report user interface **150** may be a personal electronic device (e.g., smartphone, tablet, computer), by way of a website or application, and/or at another machine **10**.

The controller(s) 68 may be configured to automatically program the device 10 in accordance with selections made at the user interface 150. In exemplary embodiments, without limitation, the controller(s) 68 may be configured to automatically program the device 10 to pass basketballs to location(s) corresponding to the location(s) of the pass receipt location indicated one of icons 162A. The controller(s) 68 may be configured to automatically record shooting performance information, such as received from one or more detectors (e.g., camera(s) 26, flappers, accelerometers, pressure sensors, switches, microphones, bimorphs, photo-eyes, ultrasonic emitters/detectors, laser emitters/detectors, proximate sensors, combinations thereof, or the like), in association with each of the locations indicated as shooting locations 1626. One or more such shooting locations 162B (e.g., 162B1, 162B2, etc.) may be utilized.

In exemplary embodiments, without limitation, the detector(s) may be configured to detect if a shot is successfully made. The controller(s) 68 may be configured to assume that a shot was missed if a certain amount of time passes without recording a made shot and/or a second pass is made before a made shot is detected. Alternatively, or additionally, the detector(s) may be configured to actively detect missed shots. Essentially, the controller(s) 68 may be configured to assume that the player(s) took shots from the indicated shooting locations 1626. The detector(s) and/or controller(s) 68 may be unable to verify if a player moves from the indicated shooting locations 1626.

While passes are made to a given location 162A, shooting statistics may instead be stored for different location(s) 1626. This may facilitate passing drills and/or off the dribble shooting, by way of non-limiting example. For example, without limitation, a first player may catch basketball passes as a catch and pass location 162A and pass those basketballs to player(s) at the shooting location(s) 1626 for those players to catch and shoot. Thus, the user interface 150 may permit accurate recording of the shooting attempts at the shooting location(s) 1626 rather than the passing location 162A. A single or multiple ones of the catch and pass locations 162A and/or shooting locations 1626 may be utilized in any arrangement to create a wide variety of drills.

The pass receipt locations 162A may be programmed and/or indicated for uses other than catch and pass, such as but not limited to, catch and drill, catch and move, catch and jump, combinations thereof, or the like. The shooting locations 162B may be programmed and/or indicated for uses other than just shooting, such as but not limited to, move and shoot, jump shot, jab and go, combinations thereof, or the like. Any type or kind of basketball and/or exercise move, including but not off the dribble shooting and the drills and/or move described with regard to the same herein, may be associated with any of the icons 162. Any type or kind of action marker 91, travel path 92, indicator 191, combinations thereof, or the like may be provided to indicate the same.

The controller(s) 68 may be configured to record shooting performance information based on the order of the shooting location indicated ones of the icons 1628. For example, without limitation, where a catch and pass locations 162A is established and two shooting locations 162B1 and 162B2 are established, the device 10 may be configured to record shooting performance information associated with a first pass at the first shooting location 162B1 and shooting performance information associated with a second pass at the second shooting location 162B2. This may be repeated for each pass for each shooting location 162B. This may be repeated over multiple iterations. For example, without

limitation, if two shooting locations 162B are selected and eight passes are provided, shooting performance associated with passes 1, 3, 5, and 7 may be recorded at the first one of the shooting locations 162B1 and shooting performance associated with passes 2, 4, 6, and 8 may be recorded at the first one of the shooting locations 162B2. The total number of passes may be selected by the user at the user interface 150, such as at the number of passes option 146, and/or automatically programmed. This may be used conjunction with any number, type, order, arrangement, or the like of such icons 162.

A tempo option 144 may be provided which permits adjustment of time between passes (e.g., number of seconds). An option for adjusting the tempo 147 during an active drill may be provided.

A point value may be associated with each of the shooting attempts based on a point value associated with each of the shooting location ones of the icons 162B, though such is not required. Such point values may be used for determining a player score and/or categorizing shooting statistics, thereby providing ability to separately generate statistics for 2-point attempts, 3-point attempts, foul line attempts, combinations thereof, or the like, by way of non-limiting example. Alternatively, a default point (e.g., 1 or 2) may be assigned to each pass.

The number of passes to be made may be manually or automatically selected, and/or the controller(s) 68 may be configured to continue passing once a start 142 option is selected until a pause 147 and/or stop 142 option is selected.

The locations of the icons 162 may be revised, such as prior to initiating a drill, which may be provided by selecting the start/stop option 142 by way of non-limiting example. Revision may include relocating icons 162, redesignating icons 162 (e.g., nature, order, point value, etc.), adding more icons 162, changing drills, removing icons, combinations thereof, or the like. A clear locations options 143 may be provided. A pause option 147 may be provided to temporarily pause an active drill, which may be resumed by pressing the start option 142 and/or the pause option 147 may also serve as a resume option.

The displays 171 may include action markers 91 for passes (e.g., FIGS. 17-18), though such is not required (e.g., FIGS. 19A-19D).

The shooting performance information may be indicated as points, percentages, numbers, combinations thereof, or the like. The shooting performance information may be location specific, zone specific, cumulative for the drill, a player, team, location, zone, drill, combinations thereof, or the like. Passing drill related statistics may be recorded with an appreciate indication, such as for separate display if desired, such as part of off the drill shooting statistics or separate therefrom. After a drill is completed, and/or when paused, options may be provided to store or discard generated performance statistics. The user interface 150 may permit entry of player, team, location, or other identifying information to record in association with the generated performance statistics. The generated performance statistics may be stored locally at the device 10 and/or remote therefrom, such as at one or more remote databases or servers.

The user interface 150 may be configured to relay user selections received to the controller(s) 68 for programming operation of the device 10. Such relay may be made electronically, such as by wired and/or wireless connection. The controller(s) 68 may be configured to store and/or relay generated performance statistics to remote device(s) for storage. Such relay may be made electronically, such as by

wired and/or wireless connection. The performance information may be generated during a drill, after a drill, combinations thereof, or the like. The performance information may be user specific, drill specific, cumulative, historical, average, team specific, location specific, zone specific, combinations thereof or the like.

The detector(s) may alternatively, or additionally, include cameras and/or machine vision software, floor sensors, ultrasonic detectors, proximity detectors, radar systems, combinations thereof, or the like for automatically detecting player position and programming and/or adjusting shooting locations 162B automatically. In such embodiments, manual programming of shooting locations 1628 may not be necessary.

While a passing drill and/or catch and pass location 162A is discussed in many instances, the user interface 150, controller(s) 68, and/or other components of the passing machine 10 or otherwise may provide an ability to record shooting statistics separate from passing locations for a wide variety of drills. For example, without limitation, the player may dribble, run, skip, jump, hop, or otherwise travel from a pass location 162A to a shooting location 162B. The player may return to the pass location 162A to receive a next pass. Travel paths 92 may optionally be indicated for such activities. Alternatively, or additionally still, multiple players may be engaged, such as at the passing locations 162A and/or the shooting locations 162B. In this fashion, multiplayer and/or team exercises may be facilitated. For example, without limitation, a first player may catch a pass at a pass location 162A and dribble to a shooting location 162B1 to attempt a shot. A second player may catch a pass at the pass location 162A or another pass location 162A and dribble to the shooting location 162B1 or another shooting location 162B2 to attempt a shot.

Multiple pass locations 162A may be programmed, each may be associated with one or multiple shooting locations 1628. This may facilitate programming of a wide variety of drills.

Each pass location 162A and shooting location 162B may be associated with one or multiple players, such that performance statistics may be recorded in association with different players who may participate in a given drill.

Any steps shown and/or described herein, such as but not limited to with regard to FIG. 20, may be omitted, repeated, performed sequentially, performed simultaneously, performed in any order, or the like. Other steps may be added.

Any embodiment of the present invention may include any of the features of the other embodiments of the present invention. The exemplary embodiments herein disclosed are not intended to be exhaustive or to unnecessarily limit the scope of the invention. The exemplary embodiments were chosen and described in order to explain the principles of the present invention so that others skilled in the art may practice the invention. Having shown and described exemplary embodiments of the present invention, those skilled in the art will realize that many variations and modifications may be made to the described invention. Many of those variations and modifications will provide the same result and fall within the spirit of the claimed invention. It is the intention, therefore, to limit the invention only as indicated by the scope of the claims.

Certain operations described herein may be performed by one or more electronic devices. Each electronic device may comprise one or more processors, electronic storage devices, executable software instructions, and the like configured to perform the operations described herein. The electronic devices may be general purpose computers or specialized

computing device. The electronic devices may comprise personal computers, smartphone, tablets, databases, servers, or the like. The electronic connections and transmissions described herein may be accomplished by wired or wireless means. The computerized hardware, software, components, systems, steps, methods, and/or processes described herein may serve to improve the speed of the computerized hardware, software, systems, steps, methods, and/or processes described herein. The electronic devices, including but not necessarily limited to the electronic storage devices, databases, controllers, or the like, may comprise and/or be configured to hold, solely non-transitory signals.

What is claimed is:

1. A system for tracking off of the dribble shooting statistics, said system comprising:
an ejector for launching basketballs to pass receipt locations spaced apart about a playing area;
a user interface for receiving user selections to initiate basketball practice arrangements; and
a controller configured to, for a respective basketball practice arrangements:
receive data from said user interface indicating user selection of, on a location-by-location basis, any of the pass receipt locations for the respective basketball practice arrangement where said user intends to perform a pre-shooting basketball move immediately before or after receiving a basketball pass from said ejector;
receive data from a detector indicating made basketball shots for respective basketball practice arrangement; generate made shots values for the pass receipt locations of the respective basketball practice arrangement with the received data from the detector; and separately designate any of the made shots values corresponding to the pass receipt locations of the respective basketball practice arrangement where the data from the user interface indicated that said user intended to perform the pre-shooting basketball move.
2. The system of claim 1 wherein:
said pre-shooting basketball move includes movements simulating game conditions; and
said pre-shooting basketball move excludes purely exercise-related movements.
3. The system of claim 1 wherein:
said controller is further configured to generate a performance report comprising performance feedback derived only from separately designated made shots values for the respective basketball practice arrangement.
4. The system of claim 3 wherein:
said performance report comprises additional performance feedback derived from all of the made shots values for the respective basketball practice arrangement.
5. The system of claim 1 wherein:
said controller is further configured to generate a performance report for the respective basketball practice arrangement comprising overall shooting statistics derived from all the made shots values and separately presented shooting statistics derived from only the separately designed made shots values.
6. The system of claim 5 wherein:
said controller is configured to transmit said performance report to a personal electronic device remote from the ejector and the controller for display.

27

7. The system of claim 6 wherein:
said controller is configured to provide said user interface at the personal electronic device.
8. The system of claim 5 wherein:
said controller is configured to generate a visual depiction of at least a portion of a North American regulation basketball court at the user interface, including at least a rendering of a three-point line, and representations of said pass receipt locations at locations on said visual depiction visually correspondent with the pass receipt 10 locations at said playing area;
- said user interface comprises a touch sensitive electronic display configured to receive at least some of said user selections in a direct, physical manner at the touch sensitive electronic display while the visual depiction is 15 displayed at the touch sensitive electronic display.
9. The system of claim 8 wherein:
each of said representations are displayed at the visual depiction only after selection by said user.
10. The system of claim 8 wherein:
said performance report comprises a second visual depiction of said portion of said North American regulation basketball court; and
- said performance report comprises a percentage of made shots separately displayed for each of said pass receipt 25 locations for the respective basketball practice arrangement at locations on said second visual depiction visually correspondent with the pass receipt locations at the visual depiction.
11. The system of claim 1 wherein:
said pre-shooting basketball move comprises movement of the player from a respective one of the pass receipt locations for the respective basketball practice arrangement to another location;
- said user interface is configured to display travel path 35 information between the respective one of the pass receipt locations and the other location; and
- said controller is configured to associate the made shots values for said pass receipt locations for the respective basketball practice arrangement associated with the 40 travel path information with the other location instead of the respective pass receipt location.
12. The system of claim 1 wherein:
said controller is configured to display action markers at said user interface for any of said pass receipt locations 45 for the respective basketball practice arrangement where the data received from the user interface indicates that the user intends to perform the pre-shooting basketball move immediately before or after receiving the basketball pass from said ejector.
13. The system of claim 12 wherein:
at least one of said action markers indicates: a type of shot to be taken by the player, a pass to be made by the player to another player or location on the basketball playing area, or a simulated pick drill to be performed by the second player.
14. The system of claim 1 further comprising:
a frame directly or indirectly connected to each of: said ejector, said user interface, and said controller.
15. The system of claim 14:
wherein the frame, the ejector, the controller, and the user interface form part of a basketball launching machine; and
- further comprising:
one or more additional basketball launching machines 65 for other users to perform the respective custom basketball practice arrangement; and

28

- a scoreboard device in electronic communication with the basketball launching machine and each of the one or more additional basketball launching machines (collectively also "the basketball launching machines").
16. The system of claim 15 wherein:
said scoreboard device is configured to display a first ranking of users associated with the basketball launching machines based on all of the made shots values received from the basketball launching machines and a second ranking of the users based on only the separately designated made shots values.
17. The system of claim 1 further comprising:
the detector, wherein the detector comprises any one or more of: a camera, photo-eye, flapper, audio sensor, and proximity detector.
18. A system for tracking off of the dribble shooting statistics, said system comprising:
an ejector for launching basketballs to pass receipt locations spaced apart about a playing area;
- a user interface for receiving user selections to initiate basketball practice arrangements;
- a detector for detecting made basketball shots; and
- a controller configured to, for a respective basketball practice arrangement:
receive data from said user interface indicating user selection of, on a location-by-location basis, any of the pass receipt locations for the respective basketball practice arrangement where said user intends to perform a pre-shooting basketball move immediately before or after receiving a basketball pass from said ejector;
- receive data from a detector indicating made basketball shots for respective basketball practice arrangement; generate made shots values for the pass receipt locations of the respective basketball practice arrangement with the received data from the detector;
- separately designate any of the made shots values corresponding to the pass receipt locations of the respective basketball practice arrangement where the data from the user interface indicated that said user intended to perform the pre-shooting basketball move; and
- generate a performance report for the custom basketball practice arrangement separately presenting user performance statistics derived from only the qualified made shots values.
19. A system for tracking off of the dribble shooting statistics, said system comprising:
an ejector for launching basketballs to pass receipt locations spaced apart about a playing area;
- a user interface for receiving user selections to initiate basketball practice arrangements;
- a detector for detecting made basketball shots during performance of said custom basketball practice arrangements; and
- a controller configured to, for a respective basketball practice arrangement:
receive data from said user interface indicating user selection of at least: a subset of said pass receipt locations where a user desires to receive basketball passes, and any of the pass receipt locations in the subset, on a location-by-location basis, where said user intends to perform a pre-shooting basketball move immediately before or after receiving a basketball pass from said ejector;

command said ejector to launch at least one basketball to each of said pass receipt locations in said subset in accordance with said user selections;

receive data from said detector indicating made basketball shots;

5 generate a made shots value for each of said pass receipt locations in said subset in accordance with the received data from the detector;

designate any of the made basketball shots values corresponding to said pass receipt locations in said 10 subset where the data from said user interface indicates that said user intends to perform a pre-shooting basketball move immediately before or after receiving a basketball pass from said ejector with an off the dribble shooting qualifier; and

15 generate a performance report for the custom basketball practice arrangement juxtaposing performance statistics derived only from the made shots values having the off the dribble shooting qualifier from additional performance statistics derived from all of 20 the made shots values.
